SCHOOL DESK OR THE LIKE

Carl W. Sundberg and Montgomery Ferar, Southfield,
Mich., assignors to American Seating Company, Grand Rapids, Mich., a corporation of New Jersey

Filed July 26, 1963, Ser. No. 75,980

Term of patent 14 years

(Cl. D33—11)

The dominant features of our design reside in the portions shown in full lines on the drawing.

This application is a continuation-in-part of our co-pending application Serial No. D. 73,128, filed January 10, 1963, now abandoned.

We claim:

The ornamental design for a school desk or the like, substantially as shown and described.
